(57) **ABSTRACT**

A plastic cleaning method for cleaning a plastic article in an automatic dishwashing machine is provided, comprising: selecting an automatic dishwashing composition for cleaning plastic, wherein the automatic dishwashing composition, comprises: a builder; a phosphonate a nonionic surfactant; and a dispersant polymer comprising: (a) 60 to 98 wt % of structural units of formula I

wherein each R¹ is independently selected from a hydrogen and a —CH₃ group; and (b) 2 to 40 wt % of structural units of formula II

wherein each R² is independently selected from an alkyl group with at least 4 carbon atoms and wherein each R³ is independently selected from a hydrogen and a methyl group.

PLASTIC CLEANING METHOD USING
DISPERSANT COPOLYMER

This application is a 371 of PCT/US2019/036260, filed Jun. 10, 2019, which claims benefit of Ser. No. 62/690,461, filed Jun. 27, 2018.

The present invention relates to a plastic cleaning method. In particular, the present invention relates to a plastic cleaning method using an automatic dishwashing composition selected to incorporate a dispersant copolymer having reduced filming properties on plastic.

Automatic dishwashing compositions are generally recognized as a class of detergent compositions distinct from those used for fabric washing or water treatment. Automatic dishwashing compositions are expected by users to produce a spotless and film-free appearance on washed articles after a complete cleaning cycle.

Phosphate-free automatic dishwashing compositions are increasingly desirable. Phosphate-free automatic dishwashing compositions typically rely on non-phosphate builders, such as salts of citrate, carbonate, silicate, disilicate, bicarbonate, aminocarboxylates and others to sequester calcium and magnesium from hard water, and upon drying, leave an insoluble visible deposit.

Currently available polymers employed in phosphate-free automatic dishwashing compositions to combat the formation of undesirable deposits on glassware include polyacrylic acid polymers and copolymers of acrylic acid and 2-acrylamido-2-methylpropane sulfonic acid (AMPS) and sodium styrene sulfonate (SSS). Polyacrylic acid polymers, however, fail to prevent certain film deposits on glassware (e.g., magnesium disilicate and calcium phosphonate scales), which present as transparent blue to blue/white films on glassware and brown films on stainless steel. Copolymers of acrylic acid with sulfonated monomers, while excellent at silicate and phosphonate scale prevention, such copolymers are not particularly effective at carbonate scale prevention. In addition, such polymers tend to have a negative impact on spotting, requiring the use of strong chelants or specialized surfactants, which lead to undesirable increases in the overall cost of the dishwashing composition.

Accordingly there remains a need for new plastic cleaning methods in automatic dish washers using formulations containing dispersant copolymers having enhanced filming properties on plastics. In particular, there remains a need for new plastic cleaning methods for use in automatic dishwashers using formulations containing dispersant copolymers selected for use on plastic articles, wherein the dispersant copolymers provide good filming performance when incorporated into phosphate-free formulations.

The present invention provides a plastic cleaning method for cleaning a plastic article in an automatic dishwashing machine, comprising: selecting an automatic dishwashing composition for cleaning plastic, wherein the automatic dishwashing composition, comprises: a builder; a phosphonate; a nonionic surfactant; and a dispersant polymer comprising: (a) 60 to 98 wt % of structural units of formula I

I

2

wherein each R¹ is independently selected from a hydrogen and a —CH₃ group; and (b) 2 to 40 wt % of structural units of formula II

II

wherein each R² is independently selected from an alkyl group with at least 4 carbon atoms and wherein each R³ is independently selected from a hydrogen and a methyl group.

The present invention provides a plastic cleaning method for cleaning a plastic article in an automatic dishwashing machine, comprising: (A) selecting an automatic dishwashing composition for cleaning plastic, wherein the automatic dishwashing composition, comprises: a builder; a phosphonate; a nonionic surfactant; and a dispersant polymer comprising: (a) 60 to 98 wt % of structural units of formula I, wherein each R¹ is independently selected from a hydrogen and a —CH₃ group; and (b) 2 to 40 wt % of structural units of formula II, wherein each R² is independently selected from an alkyl group with at least 4 carbon atoms and wherein each R³ is independently selected from a hydrogen and a methyl group; (B) providing a plastic article; and (C) applying the automatic dishwashing composition to the plastic article.

The present invention provides a plastic cleaning method for cleaning a plastic article in an automatic dishwashing machine, comprising: (A) selecting an automatic dishwashing composition for cleaning plastic, wherein the automatic dishwashing composition, comprises: 50 to 85 wt % of a builder, wherein the builder is selected from the group consisting of carbonates, bicarbonates, citrates, silicates and mixtures thereof; 0.75 to 7 wt % of a phosphonate; 1.5 to 7.5 wt % of a nonionic surfactant; and 2 to 6 wt % of a dispersant polymer; wherein the dispersant polymer comprises: (a) 75 to 95 wt % of structural units of formula I, wherein R¹ is a hydrogen in at least 98 mol % of the structural units of formula I; and (b) 5 to 25 wt % of structural units of formula II, wherein R² is a butyl group in at least 98 mol % of the structural units of formula II and wherein R³ is a hydrogen in at least 98 mol % of the structural units of formula II; and wherein the dispersant polymer has a weight average molecular weight, M_w, of 1,750 to 17,500 Daltons; (B) providing a plastic article; and (C) applying the automatic dishwashing composition to the plastic article.

55

DETAILED DESCRIPTION

Surprisingly, it has been found that, the selection of an automatic dishwashing composition comprising a dispersant polymer of the present invention (particularly phosphate-free automatic dishwashing compositions), provide surprisingly good anti-filming performance on plastic articles versus automatic dishwashing compositions comprising conventional dispersant polymers.

Unless otherwise indicated, ratios, percentages, parts, and the like are by weight. Weight percentages (or wt %) in the composition are percentages of dry weight, i.e., excluding any water that may be present in the composition. Percent-

ages of monomer units in the polymer are percentages of solids weight, i.e., excluding any water present in a polymer emulsion.

As used herein, unless otherwise indicated, the terms "weight average molecular weight" and "M_w" are used interchangeably to refer to the weight average molecular weight as measured in a conventional manner with gel permeation chromatography (GPC) and conventional standards, such as polystyrene standards. GPC techniques are discussed in detail in *Modem Size Exclusion Chromatography*, W. W. Yau, J. J. Kirkland, D. D. Bly; Wiley-Interscience, 1979, and in *A Guide to Materials Characterization and Chemical Analysis*, J. P. Sibilia; VCH, 1988, p. 81-84. Weight average molecular weights are reported herein in units of Daltons.

The term "phosphate-free" as used herein and in the appended claims means compositions containing ≤ 1 wt % (preferably, ≤ 0.5 wt %; more preferably, ≤ 0.2 wt %; still more preferably, ≤ 0.01 wt %; yet still more preferably, ≤ 0.001 wt %; most preferably, less than the detectable limit) of phosphate (measured as elemental phosphorus).

The term "structural units" as used herein and in the appended claims refers to the remnant of the indicated monomer; thus a structural unit of (meth)acrylic acid is illustrated:

wherein the dotted lines represent the points of attachment to the polymer backbone and where R¹ is a hydrogen for structural units of acrylic acid and a —CH₃ group for structural units of methacrylic acid.

Preferably, plastic cleaning method for cleaning a plastic article in an automatic dishwashing machine of the present invention, comprises: selecting an automatic dishwashing composition for cleaning plastic, wherein the automatic dishwashing composition, comprises: a builder (preferably, 1 to 97 wt % (more preferably, ≥ 10 wt %; yet more preferably, ≥ 20 wt %; still more preferably, ≥ 25 wt %; most preferably, ≥ 50 wt %; preferably, ≤ 95 wt %; more preferably, ≤ 98 wt %; still more preferably, ≤ 85 wt %; most preferably, ≤ 80 wt %), based on the dry weight of the automatic dishwashing composition, of the builder)(preferably, wherein the builder includes a mixture of at least one carbonate and at least one citrate); a phosphonate (preferably, 0.1 to 15 wt % (more preferably, 0.5 to 10 wt %; still more preferably, 0.75 to 7 wt %; most preferably, 0.9 to 5 wt %), based on the dry weight of the automatic dishwashing composition, of the phosphonate) (preferably, wherein the phosphonate has a weight average molecular weight of $\leq 1,000$ Daltons); a nonionic surfactant (preferably, 0.2 to 15 wt % (more preferably, 0.5 to 10 wt %; most preferably, 1.5 to 7.5 wt %), based on the dry weight of the automatic dishwashing composition, of the nonionic surfactant)(preferably, wherein the nonionic surfactant is a fatty alcohol alkoxylate); and a dispersant polymer (preferably, 0.5 to 15 wt % (more preferably, 0.5 to 10 wt %; still more preferably, 1 to 8 wt %; most preferably, 2 to 6 wt %), based on the dry weight of the automatic dishwashing composition, of the dispersant polymer) comprising: (a) 60 to 98 wt % (preferably, 75 to 95 wt %; more preferably, 80 to 92.5 wt %; most preferably, 85 to 91 wt %) of structural units of formula I

ably, 75 to 95 wt %; more preferably, 80 to 92.5 wt %; most preferably, 85 to 91 wt %) of structural units of formula I

wherein each R² is independently selected from an alkyl group with at least 4 carbon atoms (preferably, a —C₄₋₂₂ alkyl group; more preferably, a —C₄₋₁₈ alkyl group; yet more preferably, a —C₄₋₁₂ alkyl group; still more preferably, a —C₄₋₈ alkyl group; yet still more preferably, a —C₄₋₆ alkyl group; still yet more preferably, a —C₄₋₅ alkyl group; most preferably, a —C₄ alkyl group) and wherein each R³ is independently selected from a hydrogen and a methyl group.

Preferably, the plastic cleaning method for cleaning a plastic article in an automatic dishwashing machine of the present invention, further comprises: providing a plastic article (e.g., plastic cookware, plastic bakeware, plastic tableware, plastic dishware, plastic flatware and plastic tumblers); and, applying the automatic dishwashing composition to the plastic article. More preferably, the plastic article includes a plurality of plastic articles. Still more preferably, the plastic article includes a plastic tumbler. Most preferably, the plastic article includes a polystyrene tumbler.

Preferably, the plastic cleaning method for cleaning a plastic article in an automatic dishwashing machine of the present invention, comprises: (A) selecting an automatic dishwashing composition, wherein the automatic dishwashing composition, comprises: 50 to 85 wt % of the builder, wherein the builder is selected from the group consisting of carbonates, bicarbonates, citrates, silicates and mixtures thereof; 0.75 to 7 wt % of the phosphonate; 1.5 to 7.5 wt % of the nonionic surfactant; and 2 to 6 wt % of the dispersant polymer; wherein the dispersant polymer comprises: (a) 75 to 95 wt % of structural units of formula I, wherein R¹ is a hydrogen in at least 98 mol % of the structural units of formula I; and (b) 5 to 25 wt % of structural units of formula II, wherein R² is a butyl group in at least 98 mol % of the structural units of formula II and wherein R³ is a hydrogen in at least 98 mol % of the structural units of formula II; and wherein the dispersant polymer has a weight average molecular weight, M_w, of 1,750 to 17,500 Daltons; (B) providing a plastic article; and (C) applying the automatic dishwashing composition to the plastic article (preferably, in an automatic dishwasher); wherein the formation of film on the plastic article is inhibited.

Preferably, the plastic cleaning method for cleaning a plastic article in an automatic dishwashing machine of the present invention, the automatic dishwashing composition selected, comprises a builder. Preferably, the plastic cleaning method for cleaning a plastic article in an automatic dishwashing machine of the present invention, the automatic dishwashing composition selected, comprises a builder, wherein the builder comprises a mixture of at least one carbonate and at least one citrate. More preferably, the plastic cleaning method for cleaning a plastic article in an automatic dishwashing machine of the present invention, the automatic dishwashing composition selected, comprises a builder, wherein the builder comprises a mixture of at least one carbonate, at least one citrate and at least one citrate. Still more preferably, the plastic cleaning method for cleaning a plastic article in an automatic dishwashing machine of the present invention, the automatic dishwashing composition selected, comprises: a builder, wherein the builder comprises a mixture of sodium carbonate, sodium percarbonate and sodium citrate. Most preferably, the plastic cleaning method for cleaning a plastic article in an automatic dishwashing machine of the present invention, the automatic dishwashing composition selected, comprises: a builder, wherein the builder comprises a mixture of sodium carbonate, sodium percarbonate, sodium silicate and sodium citrate.

Preferably, the plastic cleaning method for cleaning a plastic article in an automatic dishwashing machine of the present invention, the automatic dishwashing composition selected, comprises: 1 to 97 wt %, based on the dry weight of the automatic dishwashing composition, of a builder. Preferably, the plastic cleaning method for cleaning a plastic article in an automatic dishwashing machine of the present invention, the automatic dishwashing composition selected, comprises: ≥ 1 wt % (preferably, ≥ 10 wt %; more preferably, ≥ 20 wt %; yet more preferably, ≥ 25 wt %; most preferably, ≥ 50 wt %), based on the dry weight of the automatic dishwashing composition, of the builder. Preferably, the plastic cleaning method for cleaning a plastic article in an automatic dishwashing machine of the present invention, the automatic dishwashing composition selected, comprises: ≤ 95 wt % (preferably, ≤ 90 wt %; more preferably, ≤ 85 wt %; most preferably, ≤ 80 wt %), based on the dry weight of the automatic dishwashing composition, of the builder. Weight percentages of carbonate, citrate and silicate builders are based on the actual weights of the salts, including metal ions.

The term "carbonate(s)" as used herein and in the appended claims refers to alkali metal or ammonium salts of carbonate, bicarbonate, percarbonate, and/or sesquicarbonate. Preferably, the carbonate used in the selected automatic dishwashing composition (if any) is selected from the group consisting of carbonate salts of sodium, potassium and lithium (more preferably, salts of sodium or potassium; most preferably, salts of sodium). Percarbonate used in the selected automatic dishwashing composition (if any) is selected from salts of sodium, potassium, lithium and ammonium (more preferably, salts of sodium or potassium; most preferably, salts of sodium). Most preferably, the carbonate used in the selected automatic dishwashing composition (if any) includes at least one of sodium carbonate, sodium bicarbonate and sodium percarbonate. Preferably, when the builder used in the selected automatic dishwashing composition of the present invention includes carbonate, the automatic dishwashing composition preferably, comprises 0 to 97 wt % (preferably, 10 to 75 wt %; more preferably, 25

to 60 wt %; most preferably 40 to 50 wt %), based on the dry weight of the automatic dishwashing composition, of carbonate.

The term "citrate(s)" as used herein and in the appended claims refers to alkali metal citrates. Preferably, the citrate used in the selected automatic dishwashing composition (if any) is selected from the group consisting of citrate salts of sodium, potassium and lithium (more preferably, salts of sodium or potassium; most preferably, salts of sodium). 5 More preferably, the citrate used in the selected automatic dishwashing composition (if any) is sodium citrate. Preferably, when the builder used in the selected automatic dishwashing composition of the present invention includes citrate, the selected automatic dishwashing composition 10 preferably, comprises 0 to 97 wt % (preferably, 5 to 75 wt %; more preferably, 10 to 60 wt %; most preferably 20 to 40 wt %), based on the dry weight of the automatic dishwashing composition, of the citrate.

The term "silicate(s)" as used herein and in the appended 20 claims refers to alkali metal silicates. Preferably, the silicate used in the selected automatic dishwashing composition (if any) is selected from the group consisting of silicate salts of sodium, potassium and lithium (more preferably, salts of sodium or potassium; most preferably, salts of sodium). 25 More preferably, the silicate used in the selected automatic dishwashing composition (if any) is sodium disilicate. Preferably, the builder used in the selected automatic dishwashing composition of the present invention includes a silicate. Preferably, when the builder used in the selected automatic 30 dishwashing composition of the present invention includes a silicate, the selected automatic dishwashing composition preferably, comprises 0 to 97 wt % (preferably, 0.1 to 10 wt %; more preferably, 0.5 to 7.5 wt %; most preferably 0.75 to 3 wt %), based on the dry weight of the automatic dishwashing composition, of the silicate.

Preferably, the plastic cleaning method for cleaning a plastic article in an automatic dishwashing machine of the present invention, the automatic dishwashing composition selected, comprises 0.1 to 15 wt % (more preferably, 0.5 to 40 10 wt %; still more preferably, 0.75 to 7 wt %; most preferably, 0.9 to 5 wt %), based on the dry weight of the automatic dishwashing composition, of a phosphonate. More preferably, the plastic cleaning method for cleaning a plastic article in an automatic dishwashing machine of the 45 present invention, the automatic dishwashing composition selected, comprises 0.1 to 15 wt % (more preferably, 0.5 to 10 wt %; still more preferably, 0.75 to 7 wt %; most preferably, 0.9 to 5 wt %), based on the dry weight of the automatic dishwashing composition, of a phosphonate; wherein the phosphonate is a low molecular weight having 50 a weight average molecular weight of $\leq 1,000$ Daltons. Still more preferably, the plastic cleaning method for cleaning a plastic article in an automatic dishwashing machine of the present invention, the automatic dishwashing composition selected, comprises 0.1 to 15 wt % (more preferably, 0.5 to 10 wt %; still more preferably, 0.75 to 7 wt %; most preferably, 0.9 to 5 wt %), based on the dry weight of the automatic dishwashing composition, of a phosphonate; wherein the phosphonate comprises at least one of 55 1-hydroxyethylidene-1,1-diphosphonic acid (HEDP) and a salt of 1-hydroxyethylidene-1,1-diphosphonic acid. Most preferably, the plastic cleaning method for cleaning a plastic article in an automatic dishwashing machine of the present invention, the automatic dishwashing composition selected, 60 comprises 0.1 to 15 wt % (more preferably, 0.5 to 10 wt %; still more preferably, 0.75 to 7 wt %; most preferably, 0.9 to 5 wt %), based on the dry weight of the automatic dish-

washing composition, of a phosphonate; wherein the phosphonate is selected from the group consisting of 1-hydroxyethyldene-1,1-diphosphonic acid (HEDP) and salts thereof.

Preferably, the plastic cleaning method for cleaning a plastic article in an automatic dishwashing machine of the present invention, the automatic dishwashing composition selected, comprises: 0.2 to 15 wt % (preferably, 0.5 to 10 wt %; more preferably, 1.5 to 7.5 wt %), based on the dry weight of the automatic dishwashing composition, of a nonionic surfactant. More preferably, the plastic cleaning method for cleaning a plastic article in an automatic dishwashing machine of the present invention, the automatic dishwashing composition selected, comprises: 0.2 to 15 wt % (preferably, 0.5 to 10 wt %; more preferably, 1.5 to 7.5 wt %), based on the dry weight of the automatic dishwashing composition, of the nonionic surfactant; wherein the surfactant comprises a fatty alcohol alkoxylate. Most preferably, the plastic cleaning method for cleaning a plastic article in an automatic dishwashing machine of the present invention, the automatic dishwashing composition selected, comprises: 0.2 to 15 wt % (preferably, 0.5 to 10 wt %; more preferably, 1.5 to 7.5 wt %), based on the dry weight of the automatic dishwashing composition, of the nonionic surfactant; wherein the surfactant is a fatty alcohol alkoxylate.

Preferably, the nonionic surfactant used in the selected automatic dishwashing composition of the present invention has a formula selected from

wherein M represents structural units of ethylene oxide, N represents structural units of C_{3-18} 1,2-epoxyalkane, P represents structural units of C_{6-18} alkyl glycidyl ether, x is 5 to 40, y is 0 to 20, z is 0 to 3 and R represents a C_{6-22} linear or branched alkyl group.

Preferably, the nonionic surfactant used in the selected automatic dishwashing composition of the present invention has a formula selected from

wherein M and N are structural units derived from alkylene oxides (of which one is ethylene oxide); x is 5 to 40; y is 0 to 20; R represents a C_{6-22} linear or branched alkyl group; and R' represents a group derived from the reaction of an alcohol precursor with a C_{6-22} linear or branched alkyl halide, epoxyalkane or glycidyl ether.

Preferably, the nonionic surfactant used in the selected automatic dishwashing composition of the present invention has a formula

wherein M represents structural units of ethylene oxide and x is at least three (preferably, at least five; preferably, no more than ten; more preferably, no more than eight). Preferably, wherein R and R' each have at least eight (more preferably, at least ten) carbon atoms.

Preferably, the plastic cleaning method for cleaning a plastic article in an automatic dishwashing machine of the present invention, the automatic dishwashing composition selected, includes a dispersant polymer. More preferably, the plastic cleaning method for cleaning a plastic article in an automatic dishwashing machine of the present invention, the automatic dishwashing composition selected, includes: 0.5 to 15 wt %, based on the dry weight of the automatic dishwashing composition, of a dispersant polymer. Still

more preferably, the plastic cleaning method for cleaning a plastic article in an automatic dishwashing machine of the present invention, the automatic dishwashing composition selected, includes 0.5 to 10 wt %, based on the dry weight of the automatic dishwashing composition, of a dispersant polymer. Yet more preferably, the plastic cleaning method for cleaning a plastic article in an automatic dishwashing machine of the present invention, the automatic dishwashing composition selected, includes 1 to 8 wt %, based on the dry weight of the automatic dishwashing composition, of a dispersant polymer. Most preferably, the plastic cleaning method for cleaning a plastic article in an automatic dishwashing machine of the present invention, the automatic dishwashing composition selected, includes 2 to 6 wt %, based on the dry weight of the automatic dishwashing composition, of a dispersant polymer.

Preferably, the dispersant polymer used in the selected automatic dishwashing composition of the present invention comprises 60 to 98 wt % (preferably, 75 to 95 wt %; more preferably, 80 to 92.5 wt %; most preferably, 85 to 91 wt %), based on weight of the dispersant polymer, of structural units of formula I, wherein each R¹ is independently selected from a hydrogen and a $-\text{CH}_3$ group. More preferably, the dispersant polymer used in the selected automatic dishwashing composition of the present invention comprises 60 to 98 wt % (preferably, 75 to 95 wt %; more preferably, 80 to 92.5 wt %; most preferably, 85 to 91 wt %), based on weight of the dispersant polymer, of structural units of formula I; wherein R¹ is a hydrogen in 75 to 100 mol % (preferably, 90 to 100 mol %; more preferably, 98 to 100 mol %; still more preferably, ≥ 99 mol %; most preferably, 100 mol %) of the structural units of formula I in the dispersant polymer.

Preferably, the dispersant polymer used in the selected automatic dishwashing composition of the present invention comprises 2 to 40 wt % (preferably, 5 to 25 wt %; more preferably, 7.5 to 20 wt %; most preferably, 9 to 15 wt %), based on weight of the dispersant polymer, of structural units of formula II, wherein each R² is independently selected from an alkyl group with at least 4 carbon atoms (preferably, a C_{4-22} alkyl group; more preferably, a C_{4-18} alkyl group; yet more preferably, a C_{4-12} alkyl group; still more preferably, a C_{4-8} alkyl group; yet still more preferably, a C_{4-6} alkyl group; still yet more preferably, a C_{4-5} alkyl group; most preferably, a C_4 alkyl group) and wherein each R³ is independently selected from a hydrogen and a methyl group. More preferably, the dispersant polymer used in the selected automatic dishwashing composition of the present invention comprises 2 to 40 wt % (preferably, 5 to 25 wt %; more preferably, 7.5 to 20 wt %; most preferably, 9 to 15 wt %), based on weight of the dispersant polymer, of structural units of formula II, wherein each R² is independently selected from a C_{4-22} alkyl group and wherein each R³ is independently selected from a hydrogen and a methyl group. Most preferably, the dispersant polymer used in the selected automatic dishwashing composition of the present invention comprises >10 to 40 wt % (preferably, 15 to 30 wt %; more preferably, 18 to 25 wt %; most preferably, 19 to 25 wt %), based on weight of the dispersant polymer, of structural units of formula II, wherein R² is a butyl group in 75 to 100 mol % (preferably, 90 to 100 mol %; more preferably, 98 to 100 mol %; most preferably, 100 mol %) of the structural units of formula II in the dispersant polymer; and wherein R³ is a hydrogen in 75 to 100 mol % (preferably, 90 to 100 mol %; more preferably, 98 to 100 mol %; most preferably, 100 mol %) of the structural units of formula II in the dispersant polymer.

Preferably, the dispersant polymer used in the selected automatic dishwashing composition of the present invention has a weight average molecular weight of 1,200 to 25,000 Daltons. More preferably, the dispersant polymer used in the selected automatic dishwashing composition of the present invention has a weight average molecular weight of 1,500 to 20,000 Daltons. Still more preferably, the dispersant polymer used in the selected automatic dishwashing composition of the present invention has a weight average molecular weight of 1,750 to 17,500 Daltons. Most preferably, the dispersant polymer used in the selected automatic dishwashing composition of the present invention has a weight average molecular weight of 1,900 to 15,000 Daltons.

Preferably, the dispersant polymer used in the selected automatic dishwashing composition of the present invention comprises ≤ 0.3 wt % (more preferably, ≤ 0.1 wt %; still more preferably, ≤ 0.05 wt %; yet still more preferably, ≤ 0.03 wt %; most preferably, ≤ 0.01 wt %) of structural units of multi-ethylenically unsaturated crosslinking monomer.

Preferably, the dispersant polymer used in the selected automatic dishwashing composition of the present invention comprises ≤ 1 wt % (preferably, ≤ 0.5 wt %; more preferably, ≤ 0.001 wt %; still more preferably, ≤ 0.0001 wt %; most preferably, $\leq$ the detectable limit) of structural units of sulfonated monomer. More preferably, the dispersant polymer used in the automatic dishwashing composition of the present invention comprises ≤ 1 wt % (preferably, ≤ 0.5 wt %; more preferably, ≤ 0.001 wt %; still more preferably, ≤ 0.0001 wt %; most preferably, $\leq$ the detectable limit) of structural units of sulfonated monomer selected from the group consisting of 2-acrylamido-2-methylpropane sulfonic acid (AMPS), 2-methacrylamido-2-methylpropane sulfonic acid, 4-styrenesulfonic acid, vinylsulfonic acid, 3-allyloxy sulfonic acid, 2-hydroxy-1-propane sulfonic acid (HAPS), 2-sulfoethyl(meth)acrylic acid, 2-sulfopropyl(meth)acrylic acid, 3-sulfopropyl(meth)acrylic acid, 4-sulfobutyl(meth)acrylic acid and salts thereof. Most preferably, the dispersant polymer used in the selected automatic dishwashing composition of the present invention comprises ≤ 1 wt % (preferably, ≤ 0.5 wt %; more preferably, ≤ 0.001 wt %; still more preferably, ≤ 0.0001 wt %; most preferably, $\leq$ the detectable limit) of structural units of 2-acrylamido-2-methylpropane sulfonic acid (AMPS) monomer.

Methods of making the dispersant copolymers used in the selected automatic dishwashing composition of the present invention are well known to persons skilled in the art of copolymerization.

The selected automatic dishwashing composition of the present invention, optionally further comprises an additive. Preferably, the selected automatic dishwashing composition of the present invention, further comprises an additive selected from the group consisting of an alkaline source; a bleaching agent (e.g., sodium percarbonate, sodium perborate); a bleach activator (e.g., tetraacetylene diamine (TAED)); a bleach catalyst (e.g., manganese(II) acetate, cobalt(II) chloride, bis(TACN)magnesium trioxide diacetate); an enzyme (e.g., protease, amylase, lipase, or cellulase); a foam suppressant; a coloring agent; a fragrance; an additional builder; an antibacterial agent; a filler; a deposit control polymer and mixtures thereof. More preferably, the selected automatic dishwashing composition of the present invention, further comprises an additive, wherein the additive is selected from the group consisting of a bleaching agent, a bleach activator, an enzyme, a filler and mixtures thereof. Still more preferably, the selected automatic dishwashing composition of the present invention, further comprises an additive, wherein the additive includes a bleaching

agent (e.g., sodium percarbonate, sodium perborate); a bleach activator (e.g., tetraacetylene diamine (TAED)) and an enzyme (e.g., protease, amylase, lipase, or cellulase). Most preferably, the selected automatic dishwashing composition of the present invention, further comprises an additive, wherein the additive includes a bleaching agent, wherein the bleaching agent includes sodium percarbonate; a bleach activator, wherein the bleach activator includes tetraacetylene diamine (TAED); and an enzyme, wherein the enzyme includes a protease and an amylase.

Fillers included in tablets or powders are inert, water-soluble substances, typically sodium or potassium salts (e.g., sodium sulfate, potassium sulfate, sodium chloride, potassium chloride). In tablets and powders, fillers are typically present in amounts ranging from 0 wt % to 75 wt %. Fillers included in gel formulations typically include those mentioned for use in tablets and powders and also water. Fragrances, dyes, foam suppressants, enzymes and antibacterial agents usually total no more than 10 wt %, alternatively no more than 5 wt %, of the selected automatic dishwashing composition.

The selected automatic dishwashing composition of the present invention, optionally further comprises: an alkaline source. Suitable alkaline sources include, without limitation, alkali metal carbonates and alkali metal hydroxides, such as sodium or potassium carbonate, bicarbonate, sesquicarbonate, sodium, lithium, or potassium hydroxide, or mixtures of the foregoing. Sodium hydroxide is preferred. The amount of alkaline source in the automatic dishwashing composition of the present invention (if any) is at least 1 wt % (preferably, at least 20 wt %) and up to 80 wt % (preferably, up to 60 wt %), based on the dry weight of the automatic dishwashing composition.

The selected automatic dishwashing composition of the present invention, optionally further comprises: a bleaching agent (e.g., sodium percarbonate). The amount of the bleaching agent in the automatic dishwashing composition of the present invention (if any) is preferably at a concentration of 1 to 25 wt % (more preferably, 5 to 20 wt %), based on the dry weight of the automatic dishwashing composition.

The selected automatic dishwashing composition of the present invention, optionally further comprises: a bleach activator (e.g., tetraacetylene diamine (TAED)). The amount of the bleach activator in the automatic dishwashing composition of the present invention (if any) is preferably at a concentration of 1 to 10 wt % (more preferably, 2.5 to 7.5 wt %), based on the dry weight of the automatic dishwashing composition.

Preferably, the selected automatic dishwashing composition of the present invention comprises ≤ 1 wt % (preferably, ≤ 0.5 wt %; more preferably, ≤ 0.2 wt %; still more preferably, ≤ 0.1 wt %; yet still more preferably, ≤ 0.01 wt %; most preferably, $\leq$ the detectable limit), based on the dry weight of the automatic dishwashing composition, of phosphate (measured as elemental phosphorus). Preferably, the selected automatic dishwashing composition of the present invention is phosphate free.

Preferably, the selected automatic dishwashing composition of the present invention comprises ≤ 1 wt % (preferably, ≤ 0.5 wt %; more preferably, ≤ 0.2 wt %; still more preferably, ≤ 0.1 wt %; yet still more preferably, ≤ 0.01 wt %; most preferably, $\leq$ the detectable limit), based on the dry weight of the automatic dishwashing composition, of builders selected from the group consisting of nitrilotriacetic acid; ethylenediaminetetraacetic acid; diethylenetriaminepentaacetic acid; glycine-N,N-diacyclic acid; methyl glycine-N,

11

N-diacetic acid; 2-hydroxyethyliminodiacetic acid; glutamic acid-N,N-diacetic acid; 3-hydroxy-2,2'-iminodisuccinate; S,S-ethylenediaminedisuccinate aspartic acid-diacetic acid; N,N'-ethylene diamine disuccinic acid; iminodisuccinic acid; aspartic acid; aspartic acid-N,N-diacetic acid; beta-alaninediacetic acid; polyaspartic acid; salts thereof and mixtures thereof. Most preferably, the automatic dishwashing composition of the present invention contains 0 wt % of builders selected from the group consisting of nitrilotriacetic acid; ethylenediaminetetraacetic acid; diethylenetriamine-pentaacetic acid; glycine-N,N-diacetic acid; methyl glycine-N,N-diacetic acid; 2-hydroxyethyliminodiacetic acid; glutamic acid-N,N-diacetic acid; 3-hydroxy-2,2'-iminodisuccinate; S,S-ethylenediaminedisuccinate aspartic acid-diacetic acid; N,N'-ethylene diamine disuccinic acid; iminodisuccinic acid; aspartic acid; aspartic acid-N,N-diacetic acid; beta-alaninediacetic acid; polyaspartic acid; salts thereof and mixtures thereof.

Preferably, the selected automatic dishwashing composition of the present invention has a pH (at 1 wt % in water) of at least 7 (preferably, ≥ 9 ; more preferably, ≥ 9.5). Preferably, the automatic dishwashing composition of the present invention has a pH (at 1 wt % in water) of no greater than 13.

Preferably, the selected automatic dishwashing composition of the present invention can be formulated in any typical form, e.g., as a tablet, powder, block, monodose, sachet, paste, liquid or gel. The selected automatic dishwashing compositions of the present invention are useful for cleaning ware, such as eating and cooking utensils, dishes, in an automatic dishwashing machine.

Preferably, the selected automatic dishwashing composition of the present invention are suitable for use under typical operating conditions. For example, when used in an automatic dishwashing machine, typical water temperatures during the washing process preferably are from 20° C. to 85° C., preferably 30° C. to 70° C. Typical concentrations for the automatic dishwashing composition as a percentage of total liquid in the dishwasher preferably are from 0.1 to 1 wt %, preferably from 0.2 to 0.7 wt %. With selection of an appropriate product form and addition time, the automatic dishwashing compositions of the present invention may be present in the prewash, main wash, penultimate rinse, final rinse, or any combination of these cycles.

Some embodiments of the present invention will now be described in detail in the following Examples.

The weight average molecular weight, M_w ; number average molecular weight, M_n ; and polydispersity (PDI) values reported in the Examples were measured by gel permeation chromatography (GPC) on an Agilent 1100 series LC system equipped with an Agilent 1100 series refractive index. Samples were dissolved in HPCL grade THF/FA mixture (100:5 volume/volume ratio) at a concentration of approximately 9 mg/mL and filtered through at 0.45 μ m syringe filter before injection through a 4.6 $\times$ 10 mm Shodex KF guard column, a 8.0 $\times$ 300 mm Shodex KF 803 column, a 8.0 $\times$ 300 mm Shodex KF 802 column and a 8.0 $\times$ 100 mm Shodex KF-D column. A flow rate of 1 mL/min and temperature of 40° C. were maintained. The columns were calibrated with narrow molecular weight PS standards (Easical PS-2, Polymer Laboratories, Inc.).

Comparative Examples C1-C3 and Example 1:
Dispersant Polymer Compositions

Dispersant polymer compositions used herein had the composition and weight average molecular weight as noted in TABLE 1.

Comparative Examples DC1-DC4 and Example D1: Dishwashing Performance

Dishwashing compositions were prepared in each of Comparative Examples DC1-DC4 and Example D1 having the component formulations identified in TABLE 2. The protease used in each of the component formulations was Savinase® 12T protease available from Novozymes. The amylase used in each of the component formulations was Stainzyme® 12T amylase available from Novozymes.

^cAcusol™ 445N dispersant (polyacrylic acid polymer) available from The Dow Chemical Company.

Procedure for Preparing Food Soil

The STIWA food soil described in TABLE 3 was prepared by the following procedure.

- Bringing the water to a boil.
- Mixing in a paper cup the instant gravy, the benzoic acid and the starch; and then adding the mixture to the boiling water.
- Adding the milk and margarine to the product of (b).
- Letting the product of (c) cool down to approximately 40° C., and then adding mixture to a kitchen mixer (Polytron).
- Combining in another paper cup, the egg yolk, the ketchup and the mustard and mixing with a spoon.
- Adding the product of (e) to the mixture of (d) in the blender with continuous stirring.
- Letting the product of (f) stir in the blender for 5 minutes.
- The freezing the product food soil mixture from (g).

i) 50 g of the frozen slush is placed into the dishwasher at beginning of the main wash.

TABLE 3

Ingredient	wt %
Water	70.9
Margarine	10.1
Gravy Powder	2.5
Potato Starch	0.5
Benzoic Acid	0.1
Egg Yolk	5.8
Mustard	2.5
Ketchup	2.5
Milk	5.1

Dishwashing Test Conditions

Machine: Miele SS-ADW, Model G1222SC Labor. Wash 20 at 65° C.-30 min, prewash. Water: 37° fH hardness, Ca:Mg=3:1. Food soil: 50 g of the composition noted in TABLE 3 was introduced to the wash liquor frozen in a cup. Each dishwashing composition from Comparative Examples DC1-DC4 and Example D1 were tested, dosed at 20 g per 25 wash.

Polystyrene Tumbler Filming and Spotting Evaluation

After 30 wash cycles under the above dishwashing test conditions, the polystyrene tumblers were dried in open air. After drying in open air, the polystyrene tumblers were observed in a light box with controlled illumination. The polystyrene tumblers were rated for filming and spotting according to ASTM method ranging from 1 (no film/spots) to 5 (heavily filmed/spotted). An average value of 1 to 5 for filming and spotting was determined as reported in TABLE 4.

TABLE 4

Composition	Thirty Cycle Score	
	Filming	Spotting
Comp. Example DC1	5.0	2.6
Comp. Example DC2	5.0	3.1
Comp. Example DC3	5.0	3.1
Comp. Example DC4	5.0	2.6
Example D1	2.8	2.3

50

We claim:

1. A plastic cleaning method for cleaning a plastic article in an automatic dishwashing machine, comprising:

selecting an automatic dishwashing composition for cleaning plastic, wherein the automatic dishwashing composition, comprises:

a builder, wherein the builder includes a mixture of at least one carbonate and at least one citrate;

a phosphonate;

a nonionic surfactant; and

a dispersant polymer comprising:

(a) 85 to 91 wt % of structural units of formula I

wherein each R¹ is independently selected from a hydrogen and a —CH₃ group; and

(b) 9 to 15 wt % of structural units of formula II

wherein each R² is independently selected from an alkyl group with at least 4 carbon atoms and wherein each R³ is independently selected from a hydrogen and a methyl group;

providing a plastic article, wherein the plastic article includes a polystyrene tumbler; and,

applying the automatic dishwashing composition to the plastic article.

2. The plastic cleaning method of claim 1, wherein the plastic article is a plurality of plastic articles.

3. The plastic cleaning method of claim 2, wherein the automatic dishwashing composition is selected to contain less than 0.1 wt %, based on the dry weight of the automatic dishwashing composition, of phosphate, measured as elemental phosphorus.

4. The plastic cleaning method of claim 3, wherein the dispersant polymer is selected to have a weight average molecular weight, M_w, of 1,200 to 50,000 Daltons.

5. The plastic cleaning method of claim 4, wherein the automatic dishwashing composition is selected to contain 0 wt %, based on the dry weight of the automatic dishwashing composition, of builders selected from the group consisting of nitrilotriacetic acid; ethylenediaminetetraacetic acid; diethylenetriaminepentaacetic acid; glycine-N,N-diacetic acid; methyl glycine-N,N-diacetic acid; 2-hydroxyethylimidodiacetic acid; glutamic acid-N,N-diacetic acid; 3-hydroxy-2,2'-iminodisuccinate; S,S-ethyl enediaminedisuccinate aspartic acid-diacetic acid; N,N'-ethylene diamine disuccinic acid; iminodisuccinic acid; aspartic acid; aspartic acid-N,N-diacetic acid; beta-alaninediacetic acid; polyaspartic acid; salts thereof and mixtures thereof.

6. The plastic cleaning method of claim 2, wherein the automatic dishwashing composition is selected to further comprises an additive selected from the group consisting of a bleaching agent, a bleach activator, an enzyme, a filler, and mixtures thereof.

7. The plastic cleaning method of claim 1, wherein the automatic dishwashing composition is selected to comprise: 50 to 85 wt % of the builder;

1.5 to 7.5 wt % of the nonionic surfactant; and

2 to 6 wt % of the dispersant polymer; wherein the dispersant polymer comprises:

(a) 85 to 91 wt % of structural units of formula I

15I

5

wherein R¹ is a hydrogen in at least 98 mol % of the structural units of formula I; and

(b) 9 to 15 wt % of structural units of formula II

II 15

20

wherein R² is a butyl group in at least 98 mol % of the structural units of formula II and

wherein R³ is a hydrogen in at least 98 mol % of the structural units of formula II; and

wherein the dispersant polymer has a weight average molecular weight, M_w, of 1,750 to 17,500 Daltons.
